FISHING LURE

James Clayton Pedigo, 535 W. Main St.,
Glasgow, Ky. 42141

Filed Sept. 7, 1966, Ser. No. 3,761

Term of patent 14 years

(Cl. D22—28)

FIG. 1

FIG. 2

FIG. 3

FIG. 4

FIGURE 1 is a side elevational view of a fishing lure bait embodying my new design;

FIG. 2 is a top plan view thereof;

FIG. 3 is a bottom plan view thereof; and

FIG. 4 is a front elevation thereof.

I claim:

The ornamental design for a fishing lure, as shown.
